UNITED STATES PATENT OFFICE.

AUGUST GASSMANN, OF CLEVELAND, OHIO.

COMBINED BRICK MOLD AND PRESS.

Application filed March 3, 1926. Serial No. 91,976.

The present invention relates to a combined mold and press and has for its principal object to provide a structure for molding and pressing bricks in an expeditious manner so that the work may be done quickly and with a minimum amount of labor.

Another very important object of the invention is to provide a device of this nature which will allow an operator to place the same in a supply of wet material such as concrete to mold the proper amount thereof and press the same and then lift the device from the concrete and place it on a drying rack at which time the bricks may be released from the device for drying and setting purposes.

A still further very important object of the invention is to provide a combined mold and press of this nature that is exceedingly simple in its construction, inexpensive to manufacture, strong, durable, and light, handy, and otherwise well adapted to the purpose for which it is designed.

With the above and numerous other objects in view which will appear as the description proceeds, the invention resides in certain novel features of construction, and in the combination and arrangement of parts as will be hereinafter more fully described and claimed.

In the drawing:

Figure 1 is a side elevation of the device embodying the features of my invention,

Fig. 2 is a rear elevation thereof,

Fig. 3 is an enlarged detail section taken substantially on the line 3—3 of Fig. 2,

Fig. 4 is another enlarged detail section taken substantially on the line 4—4 of Fig. 1,

Fig. 5 is a horizontal section taken substantially on the line 5—5 of Fig. 1, looking downwardly, and

Fig. 6 is a detail perspective of one of the plates used in the mold.

Referring to the accompanying drawing, it will be noted that I have illustrated by way of example a molding device for forming two bricks. It will be obvious, of course, after the device is thoroughly understood, that the structure may be modified for making one or more bricks as may be desired.

Referring in particular, now, to the example illustrated, it will be seen that 5 designates a box-like structure or mold body preferably consisting of four walls which are preferably arranged in a square formation. In the present example a partition 6 divides 55 the mold body 5 into two compartments, which are preferably equal in area. The lower ends of the walls of the compartment of the mold body 5 and the partition 6 are tapered so as to more easily divide the wet 60 material such as concrete, as will be more readily appreciated as the description proceeds.

A cover 7 is movably mounted in each compartment of the body 5 and has a block or shank portion 8 rising therefrom. As is clearly shown in Fig. 3, the upper portion of each shank or block 8 is provided at its ends with outwardly extending tongues 9. The front and rear walls of the body 5 70 are notched as is indicated at 10 for receiving the tongues 9 when the covers 7 are moved downwardly for pressing the wet material in the mold body and, therefore, the tongues 9 function as stops when abutting the bottoms of the notches 10. Angular stops 11 are affixed to the upper edges of the front and rear walls of the body 5 to extend over top of the notches for limiting the upward movement of the stop 80 tongues 9 and therefore the upward movement of the covers 7.

Bearing members 12 project upwardly from the shanks 8 for receiving the pivot pins 13 of levers 14. A pair of rods 15 85 project upwardly from each side wall of the mold body 5. The two pairs of rods 15 incline upwardly toward each other, and are attached to a cross head 16. The rods 15 are attached to their respective sides of 90 the mold body 5 by suitable elements 17. A bracket 18 is fixed to each bar 15 that is disposed adjacent the rear wall of the mold body 5. The ends of the levers 14 are pivotally engaged with the lower ends of the brackets 18 as is indicated at 19. The forward ends of the levers 14 converge toward each other as is indicated at 20 in Fig. 5, attached thereto a treadle plate 21. A spring 22 is fixed to each lever 14 adjacent the portion 20 and also to the forward bars 15 as at 23. These springs normally

hold the levers in their raised position so that the covers 7 are raised and the stop tongues 9 in abutment with the angular stops 11 as is shown to advantage in Figs. 2 5 and 3.

Within each compartment there is mounted an L-shaped plate 25 including a longer portion 26 movable along the surface of the partition 6 and a shorter portion 27 movable 10 along the inner surface of the body 5. On the upper edge of the longer portion 26 there projects upwardly a pair of ears 28. A pair of straps 29 is engaged with each pair of ears 28 as is indicated at 30. Each pair of straps incline upwardly together toward each other, and have their upper ends pivoted one on each side of the intermediate portion of a lever 31, the upper end of which is pivotally engaged with a bracket 20 32 depending from the cross head 16.

The two levers 31 cross each other as is seen to advantage in Fig. 2. The lower ends of the levers are pivotally engaged with rods 33 which extend up alongside of a handle 34 which rises from the cross head 16. A lever 35 is hingedly engaged as at 36 with an intermediate portion of the handle 34 adjacent its upper end and the rods or links 33 are engaged to the intermediate portion 25 thereof as at 37. The lever 35 is limited in its movement to a position at right angles to the handle 34 as is clearly shown in Fig. 1, and it may be swung upwardly thru an arc of approximately 90° to a position substantially parallel with the handle 34. The upper end of the handle is provided with a cross head 38.

By lifting or swinging up the lever 35, it 40 will be seen that the links 33 will be pulled upwardly for raising the plates 25. These plates are preferably movable a distance equal to the thickness of the bricks.

It is thought that the device has now been described with sufficient particularity so 45 that the operation and advantages thereof may be clearly understood. The parts are disposed as is shown in the drawing. The workman grasps the cross head 28 and lowers the mold box 5 in the mass of wet material such as concrete, and forces the mold 50 box downwardly therein so that the compartments thereof fill with the material, and the lower edges rest on the floor or bottom of the container for the material. The workman then actuates the levers 14 by standing or pressing downwardly with his foot the treadle plate 21, thereby causing the downward movement of the cover 7 to press the material in the compartments.

60 The workman can then step off the treadle 21 or release his foot therefrom, and the device is ready to be lifted from the material and carried to the desired drying place. The material in the compartment may be now 65 released by lifting upwardly upon the lever

35 so as to raise the plate 25. The device is then lifted upwardly to clear the bricks which are left behind.

The construction, operation, utility, and advantages of this invention should now be 70 clearly understood by those skilled in this art without a more detailed description thereof. The present embodiment of the invention has been disclosed in detail merely by way of example, since in actual practice 75 it attains the features of advantage enumerated as desirable in the statement of the invention and the above description.

It will be apparent that numerous changes 80 in the details of construction, and in the combination and arrangement of parts may be resorted to without departing from the spirit or scope of the invention as herein-after claimed, or sacrificing any of its advantages.

Having thus described my invention, what I claim as new is:—

1. A device of the class described including, in combination, a mold body, a cover movable in the body, a plate movable in the body, a handle projecting from the body, a foot treadle for actuating the cover, a lever on the handle, and means operable by the lever for raising the plate.

2. A device of the class described including, in combination, a mold body, a handle rising vertically from the mold body, means for attaching the handle to the mold body, a cover limitedly movable in the mold body, a treadle mechanism for moving the cover, a spring normally holding said treadle mechanism raised with said cover raised.

3. A device of the class described including, in combination, a mold body, a handle rising vertically from the mold body, means for attaching the handle to the mold body, a cover limitedly movable in the mold body, a treadle mechanism for moving the cover, a spring normally holding said treadle mechanism raised with said cover raised, a plate movable in the mold body, and means on the handle for actuating said plate to raise and lower the same in the mold body.

4. A device of the class described including, in combination, a mold box, a cover movable in the mold box, a plate movable in the mold box, means for limiting the movement of the cover, means for moving the cover, means normally holding the cover raised, and means for moving the plate.

5. A device of the class described including, in combination, a mold box, a cover movable in the mold box, means limiting the movement of the cover, a plate movable in the mold box, a super-structure on the mold box, a handle rising from the super-structure, a lever pivotally mounted on the handle, means for raising and lowering the plate, links connecting said last mentioned means with said lever for being operated

thereby, and a treadle structure for operation of the cover.

6. A device of the class described including, in combination, a mold box, a cover movable in the mold box, means limiting the movement of the cover, a plate movable in the mold box, a super-structure on the mold box, a handle rising from the super-structure, a lever pivotally mounted on the han-

dle, means for raising and lowering the plate, links connecting said last mentioned means with said lever for being operated thereby, a treadle structure for operation of the cover, means normally holding the treadle structure and cover raised. 10
15

In testimony whereof I affix my signature.

AUGUST GASSMANN.
